CLAIM

The ornamental design for a modular impeller as shown and described.

DESCRIPTION

FIG. 1 is a top perspective view of a modular impeller showing our new design;
FIG. 2 is a bottom perspective view thereof;
FIG. 3 is a right side elevational view thereof;
FIG. 4 is a left side elevational view thereof;
FIG. 5 is a front elevational view thereof;

(Continued)

FIG. 6 is a rear elevational view thereof;
 FIG. 7 is a top plan view thereof; and,
 FIG. 8 is a bottom plan view thereof.
